BOTTLE LABELING MACHINE

Winfred S. Griffith, Worcester, Mass., assignor to Pneumatic Scale Corporation, Limited, Quincy, Mass., a corporation of Massachusetts

Application April 25, 1934, Serial No. 722,344

5 Claims. (Cl. 216—54)

The present invention relates to bottle labeling machines, and has for its object to provide an improved machine of that type which is characterized by its simplicity of construction and 5 reliability of operation.

Briefly stated, the machine of the present invention distinguishes from labeling machines heretofore constructed by its provision of a novel label positioning and attaching mechanism that 10 insures the application of labels to bottles in a uniform manner. Furthermore, the several motions employed for feeding, positioning and attaching the labels to bottles are generally straight line motions, so that operation and maintenance 15 of the machine is greatly simplified. The above and other advantageous features of the invention will hereinafter more fully appear from the following description considered in connection with the accompanying drawings, in which:—

20 Fig. 1 is a view in side elevation of a bottle labeling machine embodying the invention.

Fig. 2 is a view in front elevation of the machine shown in Fig. 1.

Fig. 3 is a fragmentary view on an enlarged 25 scale of the cam shaft of the machine shown in Fig. 1.

Fig. 4 is a fragmentary sectional view along the line 4—4 of Fig. 1, looking in the direction of the arrows.

30 Fig. 5 is a vertical sectional view along the line 5—5 of Fig. 2, looking in the direction of the arrows.

Fig. 6 is a diagrammatic view showing, on an enlarged scale, the feeding of a label to a bottle.

35 Fig. 7 illustrates the positioning of a label on a bottle.

Figs. 8 and 9 illustrate the operation of the label attaching wipers.

Like reference characters refer to like parts 40 in the different figures.

Referring to the drawings, the machine comprises a base 1 on which a cam shaft 2 is rotatably supported in bearings 3, the shaft 2 being driven by gearing 4 from a cross shaft 5. The 45 shaft 5 extends beyond one side frame member 6 of the machine and carries a pulley 7, as shown in Fig. 2. The pulley 7 is driven through a belt 8 from a suitable source of power, shown herein as a motor 9 mounted on a top frame member 10 of the machine, the motor 9 serving to drive a pulley 11 around which the belt 8 passes through suitable reduction gearing 12, see Fig. 1.

The machine base 1 also carries a work support 13 mounted at the top of an upwardly extending pedestal 14 and a bottle 15 is shown as being mounted on the support 13 for operation upon by the label applying instrumentalities hereinafter described. As best shown in Fig. 2, the work support 13 is located midway between 55 the side frame members 6 of the machine, and

a supply of labels 16 is supported above and vertically in line with the bottle 15 by means of a bracket 17 carrying fingers 18. The fingers 18 are suitably adjustable for supporting different sizes of labels, and are so formed as to permit 5 the lowermost label 16 of the stack to be withdrawn separately by the action of a picking mechanism, which will next be described.

The picking mechanism consists of a pair of horizontally extending pickers 19 disposed on 10 opposite sides of the bottle support 13, each picker being carried by an arm 20 extending rearwardly and connected at its end to a slide 21. As best shown in Fig. 1, the picker slides 21 are movable on vertical rails 22, the slides being connected together at their lower ends by a cross member 23. As best shown in Fig. 3, the cross member 23 carries a roll 24 bearing on the surface of a cam 25 mounted on the shaft 2 and the cam 25 is so designed that rotation of the 15 shaft 2 imparts an up and down movement to the slides 21 carrying the pickers 19. A dwell on the cam 25 serves to arrest upward movement of the pickers 19 toward the stack of labels 16 for the purpose of gumming the same preparatory to removal of a label from the stack. 20

Adhesive is adapted to be applied to the pickers 19 by means of a gumming roll 26, best shown in Fig. 2 as being mounted on a shaft 27 rotatably supported between slides 28. The slides 28 are 25 movable on parallel horizontal rails 29 extending rearwardly beneath the upper frame member 10, and the slides 28 are connected by a cross member 30. As best shown in Fig. 1, the gumming roll slides 28 are adapted to be moved back and 30 forth by means of a lever 31 pivoted at 32, with its upper end connected to cross member 30 by means of a pin 33 received in a slot 34. The lower end of lever 31 carries a roll 35 bearing on a cam 36 mounted on the cross shaft 5. Rotation of the shaft 5, therefore, imparts a reciprocating movement to the gumming roll 26 through the slides 28, so as to cause it to receive adhesive from a suitable supply and apply it to the surfaces of the pickers 19. 40

A suitable supply of liquid adhesive is contained in a trough 37 removably mounted on rods 37a below frame member 10, and as best shown in Fig. 5, a roll 38 rotatably mounted in the trough 37 is driven by means of a chain 39 engaging a sprocket wheel 40 on one end of the roll shaft which extends beyond the trough 37. The chain 39 passes around an idler 39a and extends downwardly around a second sprocket 41 mounted on the cross shaft 5, so that the roll 38 rotates continuously in the trough 37 while the machine is running. When the slides 28 carrying the gumming roll 26 are moved to the left as viewed in Fig. 5 by the operation of the cam 36, the periphery of the roll 26 is brought into engage- 45 50 55 60

ment with the periphery of the trough roll 38, as indicated in dotted lines. As this engagement occurs, a pinion 42 mounted on one end of the gumming roll shaft 27 engages a gear 43 mounted on the shaft of the trough roll 38, so that engagement of the gumming roll 26 with the trough roll 38 is accompanied by rotative movement of the roll 26. This insures uniform distribution of the adhesive over the entire periphery of the roll 26 prior to its engagement with the pickers 19.

As previously pointed out, the cam 25 controlling up and down movement of the picker slides 21 provides a dwell, and the cam 25 is so timed with respect to the gumming roll cam 36 that the pickers 19 come to rest in line with the bottom of the gumming roll 26 when the latter is in engagement with the trough roll 38, as indicated in dotted lines in Fig. 5. Therefore, when the gumming roll 26 moves to the right as viewed in Fig. 5, its periphery passes over the upper faces of the pickers 19 to apply a uniform coating of adhesive thereto. As soon as the gumming roll 26 moves over the entire length of the pickers 19, it immediately returns to the dotted line position of Fig. 5 in engagement with the trough roll, in which it is entirely clear of the pickers. The pickers 19 thereupon complete their upward movement to engage the lowermost label 16 in the stack, so that when the pickers 19 start their downward movement, the adhesion of the label to the pickers causes the lowermost label to be removed from the stack. The pickers 19, with a label supported between them, then move downwardly to the lowermost position shown in Fig. 2, with the label held close to the upper surface of the bottle 15 on the work support 13. The label 16 is now ready for application to the surface of the bottle by means of a gripper mechanism 44 which will next be described.

As best shown in Figs. 1 and 6, a gripper 44 composed of yielding frictional material, such as rubber, extends between the pickers 19 above the label 16 supported thereon, the gripper 44 being moved to this position only after the pickers 19 have carried a label to a point just above the bottle 15. Prior to this time, the gripper 44 has occupied a retracted position indicated in dotted lines in Fig. 3, in which it is entirely out of the way of the movement of a label by the pickers 19. As best shown in Fig. 3, the gripper 44 is carried by an arm 45 pivotally connected at its lower end to a carriage 46 that is vertically movable on ways 47 provided by the picker slides 21. The carriage 46 has mounted thereon a roll 48 bearing on the surface of a cam 49 mounted on the shaft 2, so that as the shaft 2 rotates, the cam 49 imparts an up and down movement to the gripper arm 45, which movement is accompanied by turning of the arm 45 about its pivot 45a on the carriage 46.

To this end, the arm 45 is pivotally connected by means of a link 50 to one end of a floating lever 51, the other end of which is connected by a link 52 to a fixed pivot 53. The lever 51 is pivotally connected intermediate its ends to a link 54 that is in turn pivotally mounted on a slide 55 carrying a roll 56 bearing on the surface of a cam 57 on the shaft 2. The cams 49 and 57 are so designed as to impart a compound motion to the gripper arm 45, which as indicated in dotted lines in Fig. 3, insures that the gripper 44 will be withdrawn from the path of movement of the pickers 19 when the latter are moving

downwardly with a blank supported therebetween.

When the pickers 19 come to rest with a label 16 supported therebetween just above a bottle 15, the gripper 44 is moved from its retracted position to a position in which the gripper extends substantially parallel to the surface of the bottle. At this point, angular movement of the gripper arm 45 ceases, and the cam 49 alone acts on the carriage 46 carrying the gripper arm 45. This results in downward movement of the gripper, in a substantially straight line, from the position of Fig. 6 to the position of Fig. 7. As the gripper 44 so moves, it engages the label 16 midway between the pickers 19 and carries it downwardly into engagement with the surface of the bottle 15. As this movement occurs, the pickers 19 start to move upwardly to be regummed by the roll 26, but as indicated in Fig. 7, stripping of the label from the pickers 19 does not occur until after the label has been firmly clamped on the bottle 15 by the gripper 44. The action of the gripper 44 in moving downwardly in a straight line to engage a label 16, freely supported between the pickers 19, insures that the label cannot thereafter shift axially of the bottle when subsequently stripped from the pickers 19 and then operated upon by the wiping mechanism next to be described.

As best shown in Figs. 2 and 8, a pair of wipers 58 composed of flexible material, such as rubber, are each carried by an arm 59 mounted on a pivot 60 carried by a slide 61. The slide 61 is disposed in front of the picker slides 21, and is movable on vertical ways 62, as best shown in Fig. 1. The wiper arms 59 extend beyond their pivots 60 and are connected at their extremities by links 63 to a common operating pin 64 located between the pivots 60. As best shown in Fig. 3, the pin 64 is carried by an auxiliary slide 65 movable vertically on the main wiper slide 61, the auxiliary slide 65 carrying a roll 66 held in engagement with a cam 67 on shaft 2 by means of a spring 68. The main slide 61, in turn, carries a roll 69 bearing on a cam 70 on shaft 2, and the cams 67 and 70 are so designed as to impart vertical movement to both slides 61 and 65 for operating the wipers 58.

Referring now to Fig. 8, it will be seen that when the gripper 44 positions a label 16 on the bottle 15, the wipers 58 occupy a position in which they are disposed entirely outside of the zone of movement of the label. Following this, the main slide 61 moves upwardly, and as this movement is accompanied by relative downward movement of the pin 64 on the auxiliary slide 65, the wipers are moved both upwardly and towards each other, as indicated by their dotted line position in Fig. 8. Following this movement, the main slide 61 moves downwardly, thereby causing the wipers 58 to engage the extended portions of the label 16, as held on the bottle by the gripper 44, and wrap the gummed areas on the under sides of the label around the surface of the bottle, as indicated in Fig. 9. Following completion of the label wrapping movement, the wiper arms 59 are spread apart again, so that the wipers re-occupy the position of Fig. 8.

The complete cycle of operations involved in the attachment of a label 16 to a bottle 15 is thus illustrated diagrammatically in Figs. 6 to 9 inclusive, from which it is apparent that the movements of the pickers 19, gripper 44 and the wipers 58 are so related that a label is positioned above a bottle and subsequently applied thereto for each complete cycle of operations. Beginning with the

parts occupying the position of Fig. 6, it is apparent that certain elements operate coincidentally to the end that the time elapsed after the removal of a label from the stack until its application on the bottle is reduced to a minimum. Thus, while the gripper 44 is holding a gummed label in position on the bottle for operation upon by the wipers 58, the pickers 19 are moved upwardly to receive an application of adhesive from 5 the gumming roll 26, followed by continued upward movement of the pickers to engage the lowermost label in the stack. Therefore, the wipers 58 have completed the application of a gummed label to the bottle, and the gripper 44 has 10 been retracted to the dotted line position of Fig. 15 by the time the pickers 19 carrying a gummed label therebetween are starting their downward movement to position the label above the bottle 15.

In order to provide for the removal of a bottle 20 with a label applied thereto while the parts are at rest, the pulley 7 has associated therewith a one-revolution clutch 71 of suitable construction, which is under the control of an operating lever 25 72, see Fig. 2. The clutch 71 is so arranged that the cam shaft 2 will come to rest after each complete revolution thereof, with the parts occupying the position of Figs. 1 and 6,—that is to say, with a gummed label 16 supported by the pickers 19 just above the work support 13. As the parts 30 come to rest, the operator removes the bottle with a label attached by the preceding cycle of operations, and substitutes therefor an unlabeled bottle. Therefore when the clutch lever 72 is again operated, the label attaching operation begins from 35 the point shown in Fig. 6 and is carried through to completion in the manner described, simultaneously with the gumming of the pickers and their engagement with the stack of labels to remove a fresh label therefrom. In other words, the machine 40 is double acting to the extent that the label removed from the stack in one operating cycle is applied to the bottle in the next succeeding operating cycle, during which time a fresh label is gummed and picked in preparation for the next 45 succeeding cycle.

In order to permit the ready removal and replenishment of the adhesive trough 37, provision is made for lifting the bracket 17 carrying the stack of labels 16. To this end, a lever 73 mounted 50 on a fixed pivot 74 provides a curved slot 75 for receiving a roll 76 mounted on a carriage 77 supporting the bracket 17 by a rod 78. When the lever 73 is turned upwardly about the pivot 74, the roll 76 riding in the slot 75 lifts the carriage 77 55 and with it the stack of labels, so as to permit ready access to the adhesive trough 37. Normally, the lever 73 is in a substantially horizontal position, in which the stack of labels is held in position for engagement of the lowermost label 60 by the pickers 19.

From the foregoing, it is apparent that by the present invention there is provided a bottle labeling machine that is extremely effective and reliable in operation. Due to the positioning of each gummed label on a bottle by the gripper 44 65 while still supported by the pickers 19 and prior to the operation of the wipers 58, successive labels are accurately placed on the bottles. Therefore, bottles labeled by the machine present an absolutely uniform appearance, with each label occupying the same relative position on the bottle. Furthermore, the machine is particularly characterized by the utilization of straight line motions for actuating its essential elements, with

the driving mechanism located entirely clear of the work support, so that should a bottle be broken accidentally during operation of the machine, its contents will not get into the mechanism.

5

I claim:

1. In a machine of the class described, the combination with a work support and a stationary label magazine above said support and in vertical alinement therewith, of label pickers movable in a straight line between the magazine and the support to remove a label from said magazine and position it above a bottle on said support, and a gumming element having a complete reciprocatory movement for applying adhesive to said pickers during a dwell in their travel toward said magazine.

2. In a machine of the class described, the combination with a work support and a stationary label magazine above said support and in vertical alinement therewith, of label pickers movable in a straight line between the magazine and the support to remove a label from said magazine and position it above a bottle on said support, means for arresting travel of said pickers toward said magazine, and a gumming element having a complete reciprocatory movement for applying adhesive to said pickers while in their arrested position, followed by resumption of the travel of the gummed pickers to engage the lowermost label in said magazine.

3. In a machine of the class described, the combination with a work support, a label magazine, and means for removing a label from the magazine and positioning it on a bottle carried by said support with adhesive applied thereto, of a pair of wipers pivotally mounted on a slide vertically movable with respect to said work support, and a second slide movable on the first slide for imparting an angular movement to said wipers coincidentally with their straight line movement with the first slide, whereby said wipers are clear of the label on their upward movement and engage the ends of the label on their downward movement with said first-named slide.

4. In a machine of the class described, the combination with a work support and a stationary label magazine above said support and in vertical alinement therewith, of label pickers movable in a straight line between the magazine and the support, means for arresting travel of said pickers toward said magazine, a reciprocating gummer, means for imparting a complete forward and backward movement to said gummer for applying adhesive to said pickers while in their arrested position, and means for resuming travel of the gummed pickers to engage the lowermost label in said magazine, followed by removal of the engaged label as said picker moves toward said work support.

5. In a machine of the class described, the combination with a work support, a label magazine, and means for removing the label from the magazine and positioning it on a bottle carried by said support with adhesive applied thereto, of a vertically movable slide, a pair of wipers pivotally mounted on said slide, a second slide carried by said first slide and pivotally connected to said wipers, and means for imparting reciprocatory movement to both of said slides to cause said wipers when positioned above a label to move toward said label and apply it to the bottle as the first slide moves downwardly.

WINFRED S. GRIFFITH.
